UNITED STATES PATENT OFFICE.

JAMES E. CRAWLEY, OF MILWAUKEE, WISCONSIN.

WATER HEATER AND CONDENSER.

SPECIFICATION forming part of Letters Patent No. 498,534, dated May 30, 1893.

Application filed March 18, 1893. Serial No. 466,645. (No model.)

To all whom it may concern:

Be it known that I, JAMES E. CRAWLEY, a citizen of the United States, and a resident of Milwaukee, in the county of Milwaukee, and 5 in the State of Wisconsin, have invented certain new and useful Improvements in Water Heaters and Condensers; and I do hereby declare that the following is a full, clear, and exact description thereof.

10 My invention has for its object to provide a simple, economical water heater and condenser having means for the filtration of the water prior to the discharge of the same to a boiler-pump or injector; and said invention 15 consists in certain peculiarities of construction and combination of parts hereinafter described with reference to the accompanying drawings and subsequently claimed.

In the drawings: Figure 1 represents a vertical section of a water heater and condenser constructed according to my invention, the section being taken on line 1—1 of the succeeding figure, and Fig. 2, a horizontal section taken on line 2—2 of the preceding figure.

25 Referring by letter to the drawings, A represents a horizontal shell having one end thereof joined to a vertical cylinder B and a chamber C within the cylinder parallel thereto, the relative proportions of said cylinder and 30 inclosed chamber being such that a certain area of space is left between the same at all points. The shell A is provided with a water inlet b preferably on the line of its greatest elevation and adjacent to the end that is farthest from the cylinder B, this end being 35 closed except to the extent of a steam-entrance c designed for connection with the exhaust of a steam-engine, this steam-entrance being somewhat above the center of the shell.

40 That end of the shell A extended through the cylinder B and connected with the chamber C has a head-piece d rising from the bottom of said shell to a distance above the center of the same on or about level with the lower portion of the steam-entrance above 45 specified, and said shell is provided with a drain-outlet e, outside of said cylinder.

The upper end of the cylinder B is provided with a man-hole f having a steam-tight 50 closure D, and the lower end of said cylinder has an outlet g for the purpose hereinafter set forth.

The chamber C is open at the top and provided at the bottom with a valve-controlled draw-off pipe h that extends through the adjacent lower end of the inclosing cylinder. Contained within the chamber C is another vertical cylinder E that has a relief-pipe i extended from its upper head through the corresponding head of the main cylinder B, and a lateral branch j extends from the inner cylinder through the chamber C and said main cylinder, this branch being designed for connection with a boiler-pump or injector. I also show an ordinary water-gage F having 65 its laterals k joined to the inner cylinder adjacent to the branch j that extends therefrom.

Communicating with the cylinder E through its lower head is a perforated vertical tube G, and intermediate of the same and a similar tube H of larger diameter, fast to said cylinder, I arrange a body I of suitable filtering material, the latter and perforated tubes constituting a strainer.

In practice enough water is run into the 75 shell A to overflow the head-piece d at the inner end of the same and rise in the chamber C as high as the lateral branch j from the inner cylinder E, and this depth ordinarily maintained. The exhaust-steam from an engine entering the shell A at c operates to heat 80 the water therein, and so much of this steam as is not condensed within said shell passes into the chamber C to not only exert pressure on the water contained in this chamber, but 85 to also experience a certain amount of condensation, the surplus steam escaping through the open top of chamber C and passing down between the same and the main cylinder B to discharge through the outlet g and serving 90 to further heat the adjacent body of water. The increase of water in the shell A incidental to condensation of exhaust steam overflows into the chamber C, and there is a percolation of water through the strainer above 95 specified, this percolation being aided by the steam-pressure in said chamber. The water passed through the strainer rises in the cylinder E to be drawn off from the latter through the branch j, by a boiler-pump or injector.

100 From the foregoing it will be understood that there is a material condensation of exhaust-steam, and at the same time there is a heating of feed-water to a high temperature,

whereby a separation therefrom of impurities injurious to a boiler is induced, these impurities sinking of their own gravity to the bottom of the chamber C while oil and scum 5 rise to the surface of the water contained in said chamber. In addition to a separation of impurities from the water incidental to a high temperature said water is thoroughly filtered and enters the inner cylinder in the 10 purest possible condition.

The pipe *i* leading from the upper head of the inner cylinder E relieves the water in said cylinder from steam-pressure, and the chamber C is provided with an outlet *m* for 15 the escape of surplus water.

If at any time the water of condensation be not sufficient to supply the boiler-pump or injector, other water is admitted to the shell A, through the inlet *b*, from any suitable 20 source, and this supply of water coming into contact with the inflow of steam to said shell is heated to a certain temperature coincident with a material condensation of the steam.

It is possible to omit the strainer, and in 25 such cases the dependence of the cylinder E into the body of water in chamber C will prevent any floating impurities in this water from mingling with that drawn off by a boiler pump or injector, and therefore I do not wish to be 30 understood as confining myself to a construction that necessarily involves a strainer.

Having now described my invention, what I claim as new, and desire to secure by Letters Patent, is—

35 1. The combination of a horizontal shell having a steam-entrance, water-inlet and a partially open end; a vertical cylinder inclosing said end of the shell and provided with a suitably disposed outlet, a chamber of less 40 dimensions than the cylinder, but inclosed thereby parallel thereto and open at the upper end; another cylinder arranged within the chamber and communicating with the same, and a branch leading from the latter cylinder 45 through the chamber and former cylinder, substantially as set forth.

2. The combination of a horizontal shell having a steam-entrance, water-inlet and partially open end; a vertical cylinder inclosing 50 said end of the shell and provided with a suitably disposed outlet, a chamber of less dimensions than the cylinder, but inclosed thereby parallel thereto and open at the upper end; another cylinder arranged within the chamber, a strainer depending from the latter cylinder in communication with the same, a relief pipe extended from the latter cylinder to a point outside 55 the former cylinder, a branch leading from the inner cylinder through the shell and outer cylinder, and a water-gage that connects with said inner cylinder, substantially as set forth.

and a branch leading from the latter cylinder through a chamber and former cylinder, substantially as set forth.

3. The combination of a horizontal shell 60 having a steam-entrance, water-inlet and partially open end; a vertical cylinder inclosing said end of the shell and provided with a suitably disposed outlet, a chamber of less dimensions than the cylinder but inclosed 65 thereby parallel thereto and open at the upper end; another cylinder arranged within the chamber to communicate with the same, a relief-pipe extended from the latter cylinder to a point outside the former cylinder, and a 70 branch leading from the inner cylinder through the chamber and outer cylinder, substantially as set forth.

4. The combination of a horizontal shell 75 having a steam-entrance, water-inlet and partially open end; a vertical cylinder inclosing said end of the shell and provided with a suitably disposed outlet, a chamber of less dimensions than the cylinder, but inclosed 80 thereby parallel thereto and open at the upper end; another cylinder arranged within the chamber to communicate with the same, a branch leading from the latter cylinder through the shell and former cylinder, and a water-gage connected to the inner cylinder, 85 substantially as set forth.

5. The combination of a horizontal shell having a steam-entrance, water-inlet and partially open end; a vertical cylinder inclosing said end of the shell and provided with a 90 suitably disposed normally closed man-hole as well as a permanently open outlet, a chamber of less dimensions than the cylinder but inclosed thereby parallel thereto and open at its upper end, a valve-controlled draw-off pipe 95 connected to the chamber, another cylinder arranged within the chamber, a strainer depending from the latter cylinder in communication with the same, a relief pipe extended from the latter cylinder to a point outside 100 the former cylinder, a branch leading from the inner cylinder through the shell and outer cylinder, and a water-gage that connects with said inner cylinder, substantially as set forth.

In testimony that I claim the foregoing I have hereunto set my hand, at Milwaukee, in the county of Milwaukee and State of Wisconsin, in the presence of two witnesses.

JAMES E. CRAWLEY.
